UNITED STATES PATENT OFFICE.

CRANSTON H. CARPENTER, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed April 23, 1920. Serial No. 375,994.

To all whom it may concern:

Be it known that I, CRANSTON H. CARPENTER, a citizen of the United States, and a resident of Wilkinsburg, in the county of Allegheny and State of Pennsylvania, have invented a new and useful Improvement in Electric Furnaces, of which the following is a specification.

My invention relates to electric furnaces, and particularly to furnaces of the electric-resistance type in which the container for the material acts also as the resistor to furnish the heat necessary to melt or to heat-treat the material.

Another object of my invention is to provide improved means for conducting the current to and from the crucible resistor which means shall permit of being readily renewed or replaced. I am aware that a container comprising a graphite crucible has been used as a resistor but apparently little commercial success attended the use of such graphite containers as resistors which I believe to be due to the method of conducting the current into and out of the crucible.

In practicing my invention, I provide a graphite container, into which material to be melted or to be heat-treated, may be placed, and mount the same in a suitable casting. I provide improved means for making electrical contact with the crucible, these means comprising masses of electrical-conducting granular material which may be packed or tamped into close contact with part of the outer surface of the container to conduct the current to and from the crucible.

In the single sheet of drawings, Figure 1 is a cross-sectional view along the line I—I of Fig. 2 of a furnace embodying my invention; Fig. 2 is a view of the same furnace along the line II—II of Fig. 1. Fig. 3 is a view, in section, on the line III—III of Fig. 4, of a modification of a furnace embodying my invention, and Fig. 4 is a view on the line IV—IV of Fig. 3.

The supporting structure of the furnace comprises an exterior metal casing or frame 1 which encloses an outer shell 2 of heat-insulating brick and an inner shell 3 of fire brick. In the furnace shown in Figs. 1 and 2, the inner walls of the shell 3 are spaced apart to form a substantially circular chamber 4 and two lateral extensions 5 for a purpose to be hereinafter set forth. A graphite

crucible 6 is placed in the inner chamber 4, the chamber being of such outline as to conform closely to the shape of the crucible 6. In each of the extensions 5 is placed a mass 7 of electrical-conducting granular material, such as graphite or coke, and a terminal electrode 8, comprising a block of carbon or amorphous graphite, is so located that its inner end extends a relatively short distance into the well 5. The terminal electrodes 8 extend outwardly through the casting 1, and a metal terminal plate is suitably secured thereto for connection to the electric supply-circuit conductors (not shown). The granular material 7 is thoroughly tamped in place in the wells 5 so that it may closely engage not only the terminal electrode 8 but also a portion of the outer surface of the graphite crucible 6 and thus constitute a conducting path of relatively low resistance 75 therebetween.

Both the current-carrying part of the outer surface of the crucible 6 and the granular material 7 will oxidize during the operation of the furnace and, as the wells 5 are open at the top of the furnace, it is an easy matter to thoroughly pack or tamp the granular material solidly in the wells 5 as soon as sufficient oxidation and burning away of the granular material has taken place to 85 make such retamping necessary. It is also easy to remove the oxidized material and renew it in case such procedure should become necessary.

Referring particularly to Figs. 3 and 4, 90 wherein I have illustrated a modification of the device shown in Figs. 1 and 2, it may be noted that the method of conducting current to and from the graphite muffle 9 is substantially the same as described above. 95 Similar wells 5 are provided in the inner shell 3, and a mass of granular electrical-conducting material 7 is placed therein, a solid terminal electrode 8 projecting into the wells 5, as described above. The operation of the modification of my furnace, as shown in Figs. 3 and 4, is substantially the same as that shown in Figs. 1 and 2 and this modification may be used to heat-treat metal objects. If the muffle 9, which 100 comprises a member of substantially tubular shape, is placed in a horizontal position, as shown in Figs. 3 and 4, metallic objects may be placed therein or be drawn there-through to heat-treat them, and, in case 110

the muffle 9 is placed in a substantially vertical position, the articles may be drawn therethrough in a substantially vertical path and be heat-treated while in the muffle. I thus provide new and improved means for making electrical contact with an electrical conducting muffle which acts not only as a container for the material being treated but also as a resistor to generate the necessary heat. I provide also relatively simple means for insuring that the contact resistance between the muffle and the co-operating contact member shall be maintained at a relatively low value during long periods of operation of the furnace.

While I have shown a specific embodiment of my invention, various changes may be made therein without departing from the spirit and scope of my invention and I desire that only such limitations shall be placed thereon as are imposed by the prior art or are specifically set forth in the appended claims.

I claim as my invention:

25. 1. In an electric furnace, the combination with a refractory casing, of a muffle of refractory electrical-conducting material in said casing, hoppers in said casing on opposite sides of said muffle, solid carbonaceous

terminal electrodes extending into said hoppers, and a mass of electrical-conducting granular material in each of said hoppers adapted to electrically connect said electrodes and said muffle and to permit the current to traverse the walls of said muffle, said masses of granular material being in contact with said muffle over a relatively small portion of its surface.

2. In an electric furnace, the combination with a refractory casing, of a muffle of refractory electrical-conducting material comprising the resistor of said furnace, means for conducting current to and from said resistor, said current-conducting means comprising hoppers located adjacent to, and on opposite sides of, said muffle, solid carbonaceous terminal electrodes extending into said hoppers, and a mass of electrical-conducting granular material interposed between said electrodes and said muffle, said masses of granular material being of greater cross-section than the electrodes to prevent over-heating of the same.

In testimony whereof, I have hereunto subscribed my name this 30th day of March, 1920.

CRANSTON H. CARPENTER.
